US00D932313S

(12) **United States Design Patent** (10) Patent No.: **US D932,313 S**
Cartis et al. (45) Date of Patent: ** Oct. 5, 2021

(54) **BOTTLE**

(71) Applicant: **PepsiCo, Inc.**, Purchase, NY (US)

(72) Inventors: **Emilian Dan Cartis**, London (GB);
Balazs Kovacs, London (GB); **Philippe Ley**, Oostduinkerke (BE); **Ted Murphy**, Cork (IE); **Denis O'Callaghan**, Cork (IE); **Emma Casleton**, London (GB)

(73) Assignee: **PepsiCo, Inc.**, Purchase, NY (US)

(**) Term: **15 Years**

(21) Appl. No.: **29/743,545**

(22) Filed: **Jul. 22, 2020**

Related U.S. Application Data

(63) Continuation of application No. 29/691,783, filed on May 20, 2019, now Pat. No. Des. 893,307, which is a continuation of application No. 29/677,327, filed on Jan. 18, 2019, now Pat. No. Des. 893,305.

(57) **CLAIM**

The ornamental design for a bottle, as shown and described.

DESCRIPTION

FIG. 1 is a top front perspective view of a bottle showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the bottle that form no part of the claimed design.

The dot-dash broken lines in the figures show boundaries that form no part of the claimed design.

1 Claim, 7 Drawing Sheets
